UNITED STATES PATENT OFFICE.

ALBERT G. VOLTZ, OF TULSA, OKLAHOMA.

VISE.

Application filed January 22, 1923. Serial No. 614,166.

To all whom it may concern:

Be it known that I, ALBERT G. VOLTZ, a citizen of the United States, and resident of Tulsa, county of Tulsa, State of Oklahoma, have invented a certain new and useful Improvement in Vises, of which the following is a complete specification.

The present invention relates to vise constructions, and aims to provide an improved 10 device of this character in which provision is made for conveniently adjusting the operative or clamping part of the vise into different positions about a vertical axis, and also into various angular positions with relation to the horizontal and about the same axis.

It is also an object to provide an improved 20 clamping jaw of a removable character, with improved means for detachably securing the same to the supporting arm of the vise, in which connection provision is also made for so securing both jaws of the vise to their supporting arms as to permit attachment and removal of the jaws only by a movement 25 in opposite directions.

A further feature of the improved construction resides in the type of clamping jaw, the upper margin of which is of laterally inclined form, for affording a wider 30 clamping surface and also enabling the work to be positioned at such an angle as to clear the lower parts of the vise.

With these general objects in view, as well 35 as minor objects as will hereinafter appear, the invention will now be described by reference to the accompanying drawings illustrating one form of construction which I have devised for embodying the proposed features of improvement, after which those 40 parts and combinations deemed to be novel will be particularly set forth and claimed.

In the drawings—

Figure 1 is a side elevation showing a vise structure embodying the present invention, 45 and adjusted into one of its angular positions;

Figure 2 is a plan view of the same adjusted into horizontal position, and on a larger scale;

Figure 3 is a section taken on the line 50 III—III of Figure 2;

Figure 4 is a section taken on the line 55 IV—IV of Figure 3, but on a larger scale, and illustrating a piece of work in relation to one of the clamping jaws;

Figure 5 is a perspective view showing

the tongue construction of the upper end of one of the jaw-supporting arms;

Figure 6 is a perspective view of one of the clamping jaws;

Figure 7 is a perspective view of a plain clamping jaw;

Figure 8 is a section taken on the line 60 VIII—VIII of Figure 3, looking in the direction of the arrow; and

Figure 9 is a similar section looking in the opposite direction.

Referring now to the drawings in detail, these illustrate the improved vise construction as comprising a pair of relatively movable jaw-supporting arms 10, 11, the arm 11 being formed with a shank extension 12 mounted for sliding movement through a guide passage 13 provided in the base 14 forming the lower portion of the arm 10. 70 Within said passage 13 is provided a threaded lug 15 engaged by an operating screw 16 extending through the shank member 12 of the arm 11, one end of said screw 16 being journaled in an opening 17 provided in the lower end of the arm 11, and fitted with a knob 18 provided with an operating handle 19 slidably carried by said knob 18 in the usual manner.

The underside of the base portion 14 of the arm 10 is formed with an inclined surface, adapted to be supported upon a similarly inclined surface provided by the upper face of a supporting block 20, the shape of which is substantially that of a right truncated cylinder, as clearly illustrated in Figures 1 and 3. Within the underside of the base portion 14 is formed an undercut groove 21 for accommodating a plate 22 adapted to be fitted in place by insertion through the outer end of said groove 21, and formed with a socket portion 23 for pivotal engagement with the head 24 of the upper end of a pin 25, the slide plate 22 being secured in position by means of a screw 26 (see Figure 8). 80 The pin 25 extends through a plate 27 provided as a support for rotatably carrying the block 20, the plate 27 being in turn carried by the upper face of the table or bench 28. Accordingly, a suitable opening is provided in the table or bench 28 for the passage of the pin 25, the lower end of which 85

is threaded for receiving a clamping nut 29 provided with a forked handle 30 for the convenient operation of the nut 29 whenever it is desired to tighten or loosen the pin 25. The upper face of the plate 27 is 100 105 110

provided with a set of radially arranged lugs 31 for engagement with different points of the lower end of the block 20, as shown in Figure 2, the outer portions of these lugs 31 being formed with spaced ribs 32, and a third pair of ribs 33 being formed opposite the middle lug 31, for engagement with the heads of bolts 34 provided for securing the plate 27 in fixed position on top of the table 28. Opposite the middle lug 31, the plate 27 is also formed with a lug 35 for the mounting of a screw 36 fitted with an operating handle 37, whereby the screw 36 may be actuated into clamping engagement with the lower portion of the block 20, to force the latter into secure clamping engagement with the set of lugs 31.

As shown in Figure 9, the upper face of the block 20 is formed with a series of openings 40, which are designed for receiving the inner end of a latch screw 41 mounted in the lower margin of the base portion 14 of the arm 10, whereby said base portion 14 may be securely retained in any desired position to which it may be rotated about the axis of the pin 25. Preferably, the upper margin of the block 20 is provided with a series of marks 42 for indicating the position of each of the openings 40 and thus facilitating the registering of the screw 41 therewith.

Each of the supporting arms 10 and 11 is formed at its upper end with a substantially dovetailed tongue or tenon 45, tapering laterally but in opposite directions, these tongues or tenons 45 being provided for the removable mounting of a pair of jaws 46 formed with undercut tapered grooves 47 of the same taper as the tongues 45, so that the jaws 46 may be interchangeably mounted on either of the arms 10 or 11. The upper margins of these jaws 46 are inclined laterally in the same direction (see Figures 3, 4 and 6), although under some conditions it may be preferred to use jaws 46', (as illustrated in Figure 7) formed with the usual plain horizontal upper faces. In the case of the inclined upper margins, the angle of inclination is such as to cause a line drawn at right angles to the top surface of the jaw and intersecting the lower end thereof to extend clear of the shank member 12 of the arm 11, as clearly indicated in Figure 4. Preferably, the shank member 12 is formed with beveled upper corners 12' (see Figures 2 and 4), and the upper corners of the base 14 are similarly beveled, as indicated at 14', at the rear of the arm 10.

Besides having their opposed faces designed to operate as clamping surfaces for engagement with the work, the upper or outer faces of the jaws 46 may also be used as anvil faces in an obvious manner, and for lending greater support for these portions 65 of the jaws, the anvil side of the groove 47

of each jaw is extended back over the corresponding supporting arm materially farther than the lower or opposite side of the groove, and each of said supporting arms is formed with a shoulder 50 adapted for engagement with the outer or rear edge of the anvil portion of the corresponding jaw.

In the operation of the device, it will be noted that the jaws 46 may be applied to the upper ends of the supporting arms 10 and 11 only by a movement in opposite directions, due to the opposite taper of the tongues or tenons 45, so that consequently the jaws, when in clamping engagement with the work, will mutually oppose any tendency of either of the jaws to become displaced from supported engagement with the tongues 45. The jaws are thus both held securely in position, since any movement of either jaw in a direction tending to remove the same from its supporting tenon will not only be opposed by its companion jaw but will also tend to tighten the latter jaw in place. The inclined form of the upper margins of the jaws also affords a wider type of jaw, or one having a more extended engagement with the work, such as a sheet of metal 52 (see Figure 4); besides which, this angular jaw outline facilitates the positioning of the work in such a way as to clear the shank and other lower parts of the vise, as in cases where it is desired to bend the material 52 about the line of engagement with the jaws. It is apparent that the work 52 may be supported in oppositely inclined position from that shown in Figure 4 by simply reversing the arrangement of the jaws 46, that is, simply interchanging them upon the arms 10 and 11. This angular form of the jaws, and the manner in which they enable the work to be carried at an angle, as illustrated, is of importance, as in the usual construction the dropping of the work below a certain point is blocked by the lower part of the vise structure, and the clearance afforded by the applicant's construction is further increased by providing the beveled corners 12' and 14', as above explained. Of course, the beveled corners 14' are not involved except in those cases where a double bend is to be produced in the stock 52 and requiring the first bend to be extended down back of the arm 10. The mode of supporting the vise upon the truncated cylinder block 20 enables the vise to be swung into any desired position about the axis of the pin 25, which movement brings the vise structure into various different angular relations or inclinations to the horizontal, one of which is shown in Figure 1. This function of the apparatus is one of great advantage, inasmuch as it both facilitates the positioning of the work in the manner best suited to the workman, and also enables this adjustment as to

position to be effected with the least inter- 125

ference with surrounding objects. For producing this adjustment, the pin 25 is loosened by operating the nut 29, the screw 41 is retracted, and the vise then rotated to bring 5 the screw 41 opposite to one of the other marks 42, after which the vise is secured in this position by turning the screw 41 back into place or in engagement with the corresponding opening 40 and the pin 25 is 10 again tightened by operation of the nut 29. Thus the pin 25 operates not only as a retaining means for holding the vise structure upon the block 20, but also as a pivotal connection forming the pivot axis about which 15 the base portion 14 of the arm 10 rotates with reference to the top surface of the block 20. This block 20 may also be rotated upon the plate 27 and secured in any desired position upon said plate 27, so that any 20 desired angular position of the vise may be maintained while rotating the block 20 about the same axis or pin 25. By this means, it is apparent that the jaws and work engaged therewith may be rotated into any 25 desired position about the axis of the pin 25 and to any elevation between the upright or maximum elevation illustrated in Figure 3 and the lowermost or minimum elevation corresponding to that shown in Figure 1. All operations required of vise structures are thus greatly facilitated by the flexibility 30 of the structure herein described, since the jaws 46 are very easily detached, put in place or interchanged, and all of the adjustments above explained are readily effected.

As shown in Figure 3, the block 20 is formed with a sufficiently large bore for the pin 25 to prevent binding the latter within 40 the block, and thus permit free turning of the block about the axis of the pin; also, the socket member 23 is seated in a suitable recess 23' formed at the upper end of said bore, thereby preventing any sliding of the base 14 down the inclined upper face of said block. Furthermore, any turning of the pin 45 25 is prevented by means of a washer 38 secured to the under face of the bench 28 and formed with an internal tongue 38' en-

gaging a groove 25' in the lower end portion of said pin 25.

While I have shown and described what I now regard as the preferred form of embodiment of the proposed improvements, I desire to reserve the right to make all such changes or modifications as may fairly fall within the scope of the appended claims.

What I claim is:

1. A vise comprising a pair of relatively movable supporting arms, and a pair of jaws supported by said arms in parallel relation, said jaws and arms being formed with inter-engaging tongues and grooves permitting the application and removal of said jaws, said tongues being tapered in opposite directions. 60

2. A vise comprising a pair of relatively movable supporting arms, and a pair of jaws supported by said arms in parallel relation, said jaws being each provided with a laterally extending tapered tongue and said jaws being formed with tapered grooves for removable engagement with said tongues, the tongues of said arms being tapered in opposite directions. 70

3. A vise comprising a pair of relatively movable supporting arms, and a pair of jaws supported by said arms in parallel relation, the upper margins of said jaws having an inclination in the same direction laterally with reference to the line of relative movement of the jaws. 75

4. A vise comprising a pair of relatively movable supporting arms, one of said arms having a shank member slidably engaging the other arm, and a pair of jaws supported by said arms in parallel relation, the upper margins of said jaws being inclined laterally with reference to the line of relative movement of the jaws and at such an angle that parallel lines intersecting the respective ends of either of said margins at right angles thereto will both project to one side of and clear said shank member. 85

In witness whereof I hereunto affix my signature.

ALBERT G. VOLTZ.
